UNITED STATES PATENT OFFICE.

BERTRAM J. GOLDSMITH AND EMIL KOEB, OF NEW YORK, N. Y., ASSIGNORS TO PERFECT WINDOW REGULATOR CORPORATION, OF LONG ISLAND CITY, NEW YORK, A CORPORATION OF DELAWARE.

WINDOW REGULATOR.

Application filed May 27, 1925. Serial No. 33,074.

This invention relates to improvements in the art of window regulators.

It is one of the primary objects of the invention to provide a positive operating mechanism for a movable window and a co-operating positive lock to hold the parts in their adjusted positions.

It is a further object to provide an intermittent lock of this character operable by the control handle for the window.

Still another object is to provide a relatively simple construction necessitating the use of little additional mechanism without making any sacrifice in the function of the parts.

Other and more specific objects will appear from the following description considered in connection with the drawings in which:

20 Fig. 1 represents a broken elevational view of an automobile frame part embodying our invention.

Fig. 2 is a horizontal sectional view through the same.

25 Fig. 3 is an enlarged detail view of the regulating and locking mechanism.

Fig. 4 is a similar view showing the parts moved to different position.

Fig. 5 is a vertical section of the construction shown in Fig. 4.

Fig. 6 is a horizontal sectional view of the structure shown in Fig. 4.

Referring to the details of the drawings there are shown certain portions of an automobile door 8 the upper part of which includes a window opening adapted to be closed by a movable window 10 when the latter is in raised position. The window may be lowered into the window well 12 by the construction hereinafter described, being guided in such movement by means of the usual window guides 14 mounted in the frame part 8. The door and frame member 8 and window may be of any approved construction the details thereof forming no part of our present invention.

For the purpose of suitably adjusting and locking the window in any of its operative positions we provide the following mechanism. A supporting plate 16 is mounted upon one of the side members of the frame part 8 and is designed to carry the entire window controlling mechanism. This mech-

anism includes the operating handle 18 operatively connected to the window regulating arm 20 pivoted at 21 to the support 16, the outer or free end thereof carrying the roller 22 or other means designed to engage a member carried by the lower portion of the window 10. As shown this connection includes the guide member 24 carried by the transverse member 26 which embraces the lower portion of the window. As the arm 20 swings about its pivot the roller 22 causes a vertical movement of the window 10 as will be understood by those skilled in the art.

The connection between the operating hand lever 18 and the arm 20 includes the operating shaft 28 carried by the plate 16 and serving as a pivot for the hand lever 18. The shaft 28 carries an operating member 30 provided upon its surface with a series of spaced teeth 32 mounted for engagement with the teeth 34 upon the operated gear member 36. In the construction shown the gear member 36 is mounted upon the same pivot as the arm 20, the latter being secured to the gear as indicated at 38 for rotation therewith. The teeth 32 upon the operating element 30 are spaced apart further than the co-operating teeth 34 on the operated member 36 so as to provide certain lost motion between the operating shaft 28 and operated member 36. This will be more fully understood by reference to Figs. 3 and 4 showing the toothed operated member 30 moved to its different operative positions. It is to be noted that the gear member 36 is never free of the gear member 30 so as to be rotatable more than the distance of a space between the teeth 34 on the member 36. There is accordingly provided an operative connection between the handle 18 and the arm 20 by which the arm can be swung about its pivot to any extent permitted by the free end thereof.

For the purpose of providing a positive lock for the arm 20 a locking element 40 is pivoted as at 42 to the plate 16. This locking element includes the locking lug 44 formed upon an intermediate portion thereof and an actuating portion 46 preferably at the outer or free end thereof. The lug 44 is mounted to be moved into position be-

tween the teeth 34 of the operated member 36 or to be moved upwardly out of the path of movement of said teeth to lock or unlock the operated member against or for pivotal movement. The position of the lug 44 is controlled by the teeth 32 of the operating member in that the operating cam 46 is designed to be engaged by said teeth 32. The element 40 is held in engagement with the member 30 by means of the spring member 48 preferably wound upon the pivotal shaft of said element and engaging over said element as indicated at 50.

The weight of the window is counterbalanced by means of the spring 52 connected to the supporting plate as at 54 and to a remote point on the arm 50 as at 56. This spring relieves the gears 30 and 36 and handle 18 of the weight of the window.

20 The operation of the device is as follows. When it is desired to move the window to a different position the operating handle 18 is rotated to a position such that one of the teeth 31 comes under the operating cam 46 25 to raise the lug 44 from its position between the teeth 34 on the operated member 36. Just prior to or as the locking element is raised one of the teeth 32 engages a tooth of the operated member to move the same to 30 a new position. The relation of the parts at the time the operated member 36 is unlocked and being moved is shown in Fig. 4 wherein the operating member 30 is being moved clockwise as viewed in said figure. Further rotation of the handle 18 and gear member 30 rotates the operated member 36 counterclockwise and releases the latching element 40 from the tooth 32, so that the locking lug 44 drops between the next pair of 35 teeth 34 on the element 36. The gear 30 can then be rotated a limited distance as will be seen from Fig. 3, without unlocking the gear member 36 for rotation but any rotation of the gear 30 sufficiently to cause engagement 40 of the teeth 32 and 34, as seen in Fig. 4, causes one of the teeth 32 to pass beneath the cam 46 to raise the locking element 40 to unlock the same permitting the operated member 30 to be moved.

50 It will be seen that by this construction the arm 20 is normally held positively locked in its adjusted position and that it is only freed from such locked condition by a movement of the operating handle 18 to release 55 the locking element 40. This operated element 36 is accordingly intermittently locked and unlocked dependent upon the position of the operating handle 18, its shaft 28 and the gear 30.

60 While we have shown and described certain specific constructions it is to be understood that these are merely illustrative of the invention, the scope of which is defined in the appended claims.

65 We claim as our invention:

1. In a device of the character described, a frame, a window slidable therein, means operatively connected to said window for regulating the same, said means including a toothed operated member and a toothed operating member, the teeth of said operated member and operating member being enmeshed to cause the former to be rotated by rotation of the latter, and means controlled by the teeth on said operating member for locking said operated member against movement.

2. In a window regulator, a toothed operated member, a toothed operating member therefor mounted in position to have the teeth thereof engage the teeth of said operated member for operating the latter from the former, and a locking element having means to engage and lock the teeth of said operated member against rotation, said element extending to and engaging said operating member and being controlled by the rotative movements of the latter.

3. In a window regulator, an operated member operatively associated with said window for moving the same, an operating member, means for causing said operated member to rotate with said operating member, said means including a lost motion connection permitting said operating member to rotate from a normal position relatively to said operated member, to a limited extent in either direction, locking means for normally preventing rotation of said operated member, said locking means being rendered inoperative by movement of said operating member in either direction from a normal position.

4. In a window regulator, a toothed rotatable operated member, a rotatable operating shaft, a toothed rotatable operating member operatively connected thereto and adapted to mesh with the teeth on said operated member, the teeth of said operating member being spaced apart further than the teeth of said operated member to provide lost motion between said operating member and said operated member, and a locking member extending to a position to engage said operating member to be operated thereby and adapted to lock said operated member against rotation.

5. In a window regulator, a toothed rotatable operated member, a rotatable operating shaft, a lost motion connection operatively connecting said operating shaft to said operated member, and a locking member controlled by the rotation of said operating member and adapted to lock said operated member against rotation.

6. In a window regulator, a toothed rotatable operated member operatively associated with said window, a toothed rotatable operating member operatively connected to rotate said operated member, and movable to

or from a normal position relatively to said operated member, a locking dog including a part adapted to engage and lock said operated member against rotation and a part adapted to engage said operating member to be controlled thereby, said operating member releasing said locking dog from said operated member when moved in either direction from

a normal position, and means to move said locking dog into engagement with said members. 10

Signed at New York in the county of New York and State of New York this 26th day of May, A. D. 1925.

EMIL KOEB.
